UNITED STATES PATENT OFFICE.

WILLIAM A. RICHMOND AND FRANCIS P. RICHMOND, OF SAN FRANCISCO, CALIFORNIA,
ASSIGNORS TO FRANK A. BROWN, OF SAN FRANCISCO, CALIFORNIA.

COMBINED EXHIBITING AND VENDING DEVICE.

Application filed November 26, 1921, Serial No. 517,987. Renewed May 2, 1923.

To all whom it may concern:

Be it known that we, WILLIAM A. RICHMOND and FRANCIS P. RICHMOND, citizens of the United States, residing at San Francisco, in the county of San Francisco and State of California, have invented new and useful Improvements in Combined Exhibiting and Vending Devices, of which the following is a specification.

10 Our invention relates to a combined exhibiting and vending device for pictures, cards and the like and has for its principal object to provide a device of this character embodying certain amusement features 15 which will stimulate the sale of cards, pictures or the like as well as other commodities which may be featured in connection with the device.

20 A further object of this invention is to provide a device of the character described which is simple in construction, economical to manufacture and ornamental in appearance.

25 Other objects and advantages will be apparent during the course of the following description.

In the accompanying drawings forming a part of this specification, and in which like numerals are employed to designate like 30 parts throughout the same,

Fig. 1 is a view in side elevation of the device,

Fig. 2 is a cross section on the line 2—2 of Fig. 1,

35 Fig. 3 is a vertical section taken on the line 3—3 of Fig. 2,

Fig. 4 is a plan view of a sub-base forming part of our invention,

40 Fig. 5 is a detail perspective view of one of the slip columns,

Fig. 6 is a detail perspective view of the curved plate in the bottom of each of the slip columns,

45 Fig. 7 is a detail perspective view showing the face of one of the card or picture envelopes,

Fig. 8 is a similar view of the reverse side of the envelope, and

50 Fig. 9 is a perspective view of another form of picture envelope from that disclosed in Fig. 7.

In the accompanying drawings wherein for the purpose of illustration is shown a preferred embodiment of our invention, the 55 numeral 1 represents a pedestal base on

which is mounted the vertical center rod 2 the same having a threaded upper end made to receive the nut 3 for confining the cap 4 upon the series of slip columns 5 the bottoms of which are embedded in the sub-base 6. 60 The slip columns 5 are made by channel sheet members as best shown in Fig. 5 and they may be arranged around the device in any desired number. Arranged vertically in each of the slip columns 5 is a wire 65 or the like 7 the respective ends of which are turned down and fixedly embedded in the sub-base 6 and the cap 4 after the envelopes 8 have been threaded thereon as will presently be described. 70

The envelopes 8 or folders as they may be, each have an opening or hole through that end which has the flap, so that when the picture card or the like is placed in an envelope the flap may be sealed by threading the envelope on the wire 7 and when thus placed on the wire and the wire embedded in the sub-base and cap it will be impossible to obtain access into the envelope to remove the picture card or whatever has been placed therein without destroying the envelope by pulling the same from the wire. 75

Each envelope will have an open square, oblong, round or other shaped opening 9 so as to display and exhibit the picture card 80 or the like contained therein, but the envelope may also contain a hidden ticket or the like which can only be examined by buying one of the envelopes and pulling the same from the wire. The pictures displayed through the openings in the face of the envelopes may of course be observed while the envelope is on the wire. 90

Each of the slip columns will contain a multiplicity of envelopes and all of them may be either selectively pulled off the wires or any picture in any envelope may be reviewed by slipping the envelopes up on the wire or lifting the same one above another. 95

The envelopes are preferably held on a downward slant as in Fig. 1 by the curved plates 10 fixed in the bottom of each column the plates having cut away inside edges to permit the wires to pass through to the sub-base. The provision of the plates 10 makes it possible to readily lift and inspect the pictures in the envelopes prior to extracting one or more as desired. 100

The whole device is revolvable upon the pedestal 1 so that any series of pictures may 110

be conveniently turned to a position where they may be observed without walking around the device.

We of course appreciate that our device 5 may be used for various purposes such as above described and further a rather elaborate and unique game of chance may be practised. By inserting certain "lucky" 10 tickets or the like in the envelopes so that the purchaser may make a selective withdrawal of the envelopes in hopes of drawing a ticket which would entitle him to a rebate on the purchase price of the envelope or some other listed article carried in stock by 15 the vendor. In any event the picture contained in the envelope would ordinarily represent a value received purchase to the vendee.

It is to be understood that the form of 20 our invention herewith shown and described is to be taken as a preferred example of the same, and that various changes in the shape, size and arrangement of parts may be resorted to without departing from the spirit 25 of the invention or the scope of the subjoined claims.

Having thus described our invention, we claim:

1. In a device of the character described, 30 an exhibiting and vending rack comprising

a plurality of channel members, a wire spaced within each of said channel members for retaining articles to be vended, a bifurcated plate mounted in the lower extremity of each of said channel members and adapted to straddle said wire, said plates being positioned at a substantially acute angle with respect to said wire. 35

2. In a device of the character described, an exhibiting and vending rack comprising 40 a base, a vertical rod mounted in said base, spaced members rotatably mounted on said rod, parallel slots formed in opposing faces of said spaced members, a second set of parallel slots formed at an angle of 90° to said 45 first mentioned slots, channel members mounted between said spaced members and held in said parallel slots in such a manner that the rear corners of one of said channel members abuts the rear corner of the next 50 adjacent channel member, a vertical wire extending between said spaced members and spaced within each of said channel members and adapted to receive window envelopes threaded thereon. 55

In testimony whereof we affix our signatures.

WILLIAM A. RICHMOND,
FRANCIS P. RICHMOND.
